(57) **CLAIM**

The ornamental design for an interactive or multiservice digital terminal, as shown and described.

DESCRIPTION

FIG. 1 is a front perspective view of an interactive or multiservice digital terminals showing my new design.

FIG. 2 is a rear perspective view of the interactive or multiservice digital terminals.

FIG. 3 is a front view of the interactive or multiservice digital terminals.

FIG. 4 is a bottom view of the interactive or multiservice digital terminals.

FIG. 5 is a top view of the interactive or multiservice digital terminals.

FIG. 6 is a left side view of the interactive or multiservice digital terminals; and,

FIG. 7 is a right side view of the interactive or multiservice digital terminals.

The large central broken line rectangle located on the underside of the base of claimed design in FIG. 4 illustrates the boundary of the claimed design and forms no part thereof. All other broken lines in the drawing figures illustrate portions of the interactive or multiservice digital terminal which form no part of the claimed design.
